ADVERTISING AND DISPLAY DEVICE

Julius Schweiger, Budapest, Hungary

Application March 8, 1938, Serial No. 194,558
In Austria July 14, 1937

3 Claims. (Cl. 40—39)

In the art of advertising it is known that an advertisement which is constantly moving has a far greater power of attracting attention than one which is stationary. Also that an advertisement which moves only intermittently is even more likely to attract attention than one which is constantly moving. Now, if this advantageous characteristic of the intermittently moved advertisement is combined with the attraction which is exerted upon the spectator by means of a peculiar method of producing the intermittent movement, so that he waits for the moment when the movement is initiated in order to see how it is caused, the effect of the advertisement is considerably enhanced.

The present invention provides in a novel way such an advertisement and its principal characteristic consists in that the rotatable advertising text or picture carrying member or carrier of an advertising device, which is preferably to be placed in a show window, is influenced by an outside source of power for example heat, light, pressure or the like which causes it to move from its stationary position into an unstable position so as to tilt the rotatable advertisement carrier and thus to attract the undivided attention of the spectator to the advertisement.

For this purpose the advertising text or picture carrier is according to the invention preferably formed of a closed system of containers advantageously made of glass and connected to one another by means of connecting tubes and suitably mounted so as to be able to rotate around a horizontal axis passing through the centre of gravity. Said system preferably contains a volatile liquid which boils at low temperature and is placed under a reduced pressure, while a source of heat is placed under the system of containers in order to bring the condensed vapors up into the less heated upper vessel of the system, so that an unstable condition is caused in the system by locating the mass center of said system above the pivotal axis thereof under the action of the boiling and thereby cause the system to rotate or capsize about its pivotal axis.

In the accompanying drawing a few embodiments of advertising devices according to the invention are shown by way of example.

Figures 1 and 2 show respectively a front and side view of one embodiment.

Figures 3 and 4 a further embodiment also in front and side view.

Figures 5 and 6 are similar views of a third embodiment of the advertising device.

According to the embodiment shown in Fig-

ures 1 and 2, the cylindrical glass containers *a* and *b* which are arranged parallel to one another and connected by the tubes *c*, form a closed system of containers, in which a liquid which boils at low temperature and pressure is placed under reduced pressure. This closed system of containers at the same time forms the framework for the advertising text or picture carrier which is placed directly or indirectly on a plate *d* which is attached to the connecting tubes *c* by means of the clips *e*. These clips are provided with pivots *f* upon which the whole system of containers is rotatably mounted on the two uprights *h* which are attached to the base *g* of the frame. A cylindrical housing *i* is attached to the base *g* and encloses a source of light, for example an electric light bulb *k*.

When the advertising device is to be set in motion, the highly volatile liquid having taken up the position in the cylindrical vessel *b* as indicated in Figures 1 and 2 the current for the electric bulb *k* is switched on. The heat radiated by the bulb *k* passes through a funnel-shaped member *l* mounted over an opening in the housing *i* and thus reach the vessel *b*, thereby vaporizing the liquid contained therein under a suitable reduced pressure. The vapours condense in the less heated upper vessel *a* whereby the former stable condition of the system of containers is brought into an unstable condition, which in turn causes the system to capsize. This imparts an oscillating motion to the system of containers during which the advertising text or picture is illuminated from below by the electric bulb. The system then comes to rest, and in this position it is the vessel *a* which receives the greater heat so that the above mentioned movement is repeated and so on. For the purpose of heating the sun's rays can also be used by training them onto the, at the time being, lower vessel by means of lenses.

The embodiment shown in Figures 3 and 4 differs from that described above only in so far as instead of the two cylindrical vessels *a* and *b*, two spheres *m* and *n* are employed which are formed into a closed circuit by means of semi-circular connecting tubes *c*, the action of this system being otherwise the same as that described above.

The embodiment illustrated in Figures 5 and 6 differs from those already described by the fact that the closed reduced pressure system consists of two hollow spheres *p* and *r* connected by a straight tube *s*. In this system the advertising text or picture carrying plate *t* which is attached

to the connecting tube ^s always presents the same face to the spectators and intermittently carries out a half turn in its own plane.

The physical or dynamical phenomenon of which use is made in the above described embodiments, i. e., that a highly volatile liquid is placed in a partial or complete vacuum in the lower container of a closed and rotatably mounted system of containers and is vaporized by means of heat so that the vapours rise into the upper container and are there condensed so as to bring the originally stable system of containers into an unstable condition whereby it is caused to capsize, makes a very favourable impression upon the spectators from the point of view of the effect of the advertising.

The intermittent movement of the rotatable advertising text or picture carrying member hereinbefore mentioned can also be effected by means of a mechanical displacement of the centre of gravity, for example by arranging movable masses upon the said carrying member, the distance of the said masses from the axis of rotation being made variable under the influence of heat. A further possibility of producing the intermittent rotational movement of the advertising text or picture carrying member is afforded by the influence of the light itself, for example by making use of the properties of selenium.

The design and material used for the advertising device can be varied in many ways within the scope of the invention. The same remark applies to the text and picture placed upon the carrying member, as well as to the illumination of the said text or picture.

Having now particularly described and ascertained the nature of my said invention and in what manner the same is to be performed, I declare that what I claim is:

1. An advertising device comprising a text or picture carrier capable of being partly rotated or tilted step by step at spaced intervals of time, means supporting said carrier including a closed frame-like vessel structure disposed in a single general plane and mounted on pivot means located in said plane having a practically horizontal axis passing through the center of gravity of the vessel structure, said frame-like vessel structure consisting of a plurality of containers interconnected by pipe means and there being a source of heat beneath said structure, and a quantity of volatile liquid under low pressure located within said vessel structure, so that the liquid in the container of the vessel structure temporarily disposed below the axis of rotation will become heated and conducted to the higher container above said axis until the latter becomes unbalanced and by superior weight from accumulated liquid causes the vessel structure and associated text or picture carrier to periodically turn over on the axis 180° and thus show alternately the opposite sides of said carrier in turn.

2. Advertising device according to claim 1, wherein the containers of the vessel structure consist of hollow glass spheres and the interconnecting pipe means comprises one or more glass tubes.

3. Advertising device according to claim 1, wherein the frame-like vessel structure including the containers, and interconnecting pipe means comprises a closed circuit in which two spaced pipes connect the containers so that the ensemble forms a frame bounding an open area adapted to be occupied by the text or picture carrier.

JULIUS SCHWEIGER.
